UNITED STATES PATENT OFFICE.

BENJAMIN F. RADFORD, OF HYDE PARK, MASSACHUSETTS.

BRAKE FOR PULLEYS.

SPECIFICATION forming part of Letters Patent No. 500,611, dated July 4, 1893.

Application filed September 15, 1892. Serial No. 446,017. (No model.)

To all whom it may concern:

Be it known that I, BENJAMIN F. RADFORD, a citizen of the United States of America, and a resident of the town of Hyde Park, in the 5 county of Norfolk and State of Massachusetts, have invented a certain new and useful Improved Brake for Pulleys, of which the following is a full, clear, and exact description.

The brake for pulleys of this invention, in 10 substance, consists of brake-shoes located to work against the inner and opposite sides of the surface of the rim of the pulley, separate carriers, one for each of said shoes, and both at one end swinging about a common central 15 or otherwise suitable pintle and at the other end joined by two toggle-arms having one end of each at a bearing on an inner face of each of said carriers, and the other end of both at a bearing on but at opposite ends of a common 20 mon-block which is held on an arm supported from said pintle and is arranged for a movement lengthwise through said arm, and in an axial direction parallel with the axis of the pulley, all substantially as hereinafter described.

In the drawings, forming part of this specification, Figure 1 is a side elevation of a pulley and a central vertical section of the brake-mechanism for and on a plane parallel with 30 the opposite sides of the pulley. Fig. 2 is a horizontal section, line 2—2, Fig. 1. Fig. 3 is an enlarged vertical section, in detail, line 3—3, Fig. 1.

In the drawings, A is a hollow or chambered 35 pulley having a hub B at and projecting from one of its sides.

C, C² are two brake-shoes made of any suitable material and each shaped to embrace a portion of the inner surface of the rim of the 40 pulley, the two portions, preferably, being of corresponding width and length. Each brake-shoe C, C² is suitably held on and projected from a similar carrier D, D². At one side of the pulley both carriers are hinged and swing 45 on a common pintle E as a center and they are held against movement lengthwise of the pintle by and between a fixed shoulder E² at one end-portion and a screw-nut E³ at the other end-portion of the pintle, and at the other side 50 of the pulley these carriers are joined together

by a toggle-lever mechanism, to be now described.

F, F² and F³ are the two arms of the toggle-lever. The toggle-arm F, F² is in two parts and the part F is adapted to be screwed lengthwise into and out of a threaded lengthwise socket of the part F², all so that the arm at pleasure may be lengthened or shortened. 55

The outer ends of each part of the two part toggle-arm F, F² and also the opposite ends of the toggle-arm F³ are severally rounded off or of hemispherical shape, and both arms are placed lengthwise and in line with each other between the ends D³, D⁴ respectively of the two brake-shoe carriers D, D², and the outer 60 rounded end of each toggle-arm is seated in a correspondingly rounded or hemispherical bearing-socket of said ends D³, D⁴ of said carriers. The ends of the toggle-arms toward each other seat in corresponding rounded or 65 hemispherical bearing-sockets at the opposite ends of a cylindrical block G, in line with said arms, and this block is at the projecting end 70 portion of a cylindrical rod or shaft H axially at right angles to the axial line of the block G and arranged to have a forward and backward movement through a suitable bearing 75 at the outer end of an arm J, forming part of the stationary frame, which arm, at its opposite end, has fixed on it the pintle E about 80 which the brake-shoe carriers swing as stated.

As is obvious, by sliding the rod H in either direction through its bearing of the arm J, the toggle-arms are simultaneously moved and if it is in one direction, by a swing of the brake-shoe carriers, the brake-shoes are forced apart and into contact with the inner surface of the rim of the pulley and if it is in the other direction the pressure on the brake-shoe is thus relieved and in consequence the brake-shoes 90 move toward each other and away from the inner surface of the rim of the pulley, all as is obvious without further explanation.

Having thus described my invention, what I claim, and desire to secure by Letters Patent, is—

The combination with a pulley, of a brake and toggle lever mechanism, consisting of brake-shoes located to work on the wheel at opposite sides of the inner surface of its rim, 100

a carrier for each brake-shoe and both at one end adapted to swing on a common pintle E, two toggle-arms extending between the outer ends of said brake-shoe carriers and both, at 5 one end, having a bearing on said ends of said carriers, a block G located between the ends of the toggle levers which are toward each other, and said ends having bearings on opposite ends of said block, a rod H carrying 10 said block G and extending therefrom in a direction axially parallel to the axis of the pulley and a stationary arm J having fixed on it, at one end the pintle E of the brake-shoe carriers and at the other end receiving and supporting the rod H, substantially as described, 15 for the purposes specified.

In testimony whereof I have hereunto set my hand in the presence of two subscribing witnesses.

BENJ. F. RADFORD.
